UNITED STATES PATENT OFFICE.

JEAN HAMA, OF NEW YORK, N. Y.

DESIGN FOR A WATCH-CHAIN.

SPECIFICATION forming part of Design No. 36,825, dated March 1, 1904.

Application filed December 15, 1903. Serial No. 185,319. Term of patent 3½ years.

To all whom it may concern:

Be it known that I, JEAN HAMA, a citizen of the United States, residing in the borough of Manhattan, city, county, and State of New York, have invented a certain new, original, and ornamental Design for Watch-Chains, of which the following is a specification, reference being had to the accompanying drawings, forming a part thereof.

10 In said drawings, Figure 1 is a view in elevation of the chain, showing one side of the

medals of which the same is composed; and Fig. 2 is also a view in elevation of the chain, but showing the obverse sides of the medals.

I claim—

15 The ornamental design for a watch-chain, as shown.

JEAN HAMA.

In presence of—

JOHN M. SCOBLE,
LUCIUS E. VARNEY.
